UNITED STATES PATENT OFFICE.

MEADER R. AKEY, OF SACRAMENTO, AND HERMAN KATZ, OF OAKLAND, CALIFORNIA.

BENDING MACHINE.

Application filed August 5, 1919, Serial No. 315,488. Renewed December 14, 1922.

To all whom it may concern:

Be it known that we, MEADER R. AKEY, a citizen of the United States, and a resident of Sacramento, county of Sacramento, State 5 of California, and HERMAN KATZ, a citizen of the United States, and a resident of Oakland, county of Alameda, and State of California, have invented a new and useful Bending Machine, of which the following is a 10 specification.

Our invention relates to apparatus for bending structural steel shapes.

An object of the invention is to provide a machine for rapidly and accurately bending 15 structural steel shapes, especially angles and channels.

The invention possesses other features of advantage, some of which, with the foregoing, will be set forth in the following description of the preferred form of our invention which is illustrated in the drawings accompanying and forming part of the 20 description. It is to be understood that we do not limit ourselves to the showing made by the said drawings and description, as we 25 may adopt variations of the preferred form within the scope of our invention as set forth in the claims.

Referring to the drawings:

Figure 1 is a plan view of the bending machine of our invention. Figure 2 is a vertical sectional view taken in the plane indicated by the line 2—2 of Figure 1. Figure 3 is a plan view of a portion of the machine, showing the bed or foundation plate and removable forms. Figure 4 is a vertical sectional view taken transversely through a portion of the apparatus in a plane indicated by the line 4—4 of Figure 2. Figure 5 is a vertical sectional view taken transversely through a portion of the apparatus in a plane indicated by the line 5—5 of Figure 2, and showing a hoisting chain attached to the apparatus. Figure 6 is a plan view, partly in section, and on an enlarged scale of a portion of the guide arms. Figure 7 is a vertical sectional view through one of the guide boxes, taken in a plane indicated by the line 7—7 of Figure 6. Figure 8 is a vertical sectional view similar to Figure 2, but showing a modified form of apparatus. Figure 9 is a vertical sectional view similar to Figure 7 but showing a modified form of guide box used with the modified form of machine 55 shown in Figure 8. Figure 10 is a plan view of a portion of another modified form of the

apparatus. Figure 11 is a vertical sectional view through one of the guide boxes of the structure shown in Figure 10, the plane of section being indicated by the line 11—11 of that figure. Figure 12 is a vertical sectional view taken in the plane indicated by the line 12—12 of Figure 10.

Referring first to the structure shown in Figures 1 to 7 inclusive, the bending machine comprises a foundation or bed plate 2 upon which a semi-annular plate 3 provided with gear teeth 4 is pivotally mounted by pins 6. During the use of the bending machine the gear plate 3 is secured in position upon the bed plate by a key 7 passed through a vertical stud 8. The under side of the gear plate is formed to accommodate the segmental or sectional forms 9, two of which are used in the present instance. The forms each comprise a segmental plate provided with a lug 11 adapted to engage in a recess formed in the bed plate, to fix the position of the forms thereon, and also provided with a peripheral flange 13, conically formed on the inner face 14, and adapted to lie against the similarly formed under side of the gear plate 3. As shown in Figure 2 the short vertical leg 16 of the angle which is to be bent, engages the peripheral surface of the form flange 13, and the long horizontal leg 17 of the angle lies between the lower face of the form and the upper face of the edge 18 of the bed plate.

Slidably mounted in the ways 19 of the plate is a block 21. A shaft 22 is rotatable in the block and is threaded through the loose bridge 23, adapted to seat against the lugs 24 on the bed plate. A handle 26 is provided for turning the shaft to move the block 21 toward the lugs. Pivotally mounted on the block 21 for movement in a vertical plane is a saddle 27, and pivotally mounted on the saddle for movement in a horizontal plane are twin arms 28 preferably formed of cylindrical pipe. In slidable engagement with each arm 28 is a sleeve 29. A screw 31 rotatably fixed in the end of the sleeve and threaded through a block 32 closing the end of the arm provides means for adjusting the sleeve longitudinally on the arm. Secured to each sleeve by suitable clamps 33 and spokes 34 is a grooved rim 36 covering about 90°. Cables 37 passing over suitably disposed pulleys 38 and 39 and connected to a winch (not shown) are disposed upon the rims 36 and secured thereto at the

far end adjacent the outer end of the arm sleeves 29. Fixed on each sleeve 29 is a bracket 41, on the outer end of which is pivoted a box 42 adapted to enclose the angle 16-17 which is to be bent. As shown in Figures 6 and 7, the box is provided with a hinged cover 43 adapted to be held close against the shape by latches 44. Rollers 46 are preferably suitably mounted in the box 10 to lessen the friction during the sliding movement of the box on the shape when it is being bent. The box is so formed on the inside as shown by the dotted line 47 that it can be swung into engagement with the 15 shape after the latter is placed in the machine, the shoulder 48 preventing the box swinging past the desired position in which it is perpendicular to the shape. The function of the brackets and guide boxes is to 20 retain the shape which is being operated upon in the same horizontal plane so that distortion of the angle is prevented.

Mounted on each bracket 41 is a roller 51 so placed as to lie opposite the peripheral 25 face of the forms 9. The rollers are provided with gear teeth 52 adapted to mesh with the teeth 4 of the plate 3 when the rollers are moved into contact with the angle lying against the forms. In order to raise 30 and lower the toothed plate and the overlying pivoted structure an eye 53 is arranged in the toothed plate adapted to be caught by the hook 54 on the end of the chain 56 running to a suitably arranged 35 winch (not shown). The hook 54 carries a gravity operated yoke 57 adapted to engage the sleeves 29 to prevent them from spreading.

Operation: The forms 9 being placed in 40 position on the bed plate, the pivoted gear plate 3 is lowered and locked flat upon the bed plate by the key 7, and the heated angle to be bent is pushed into position on the forms and the boxes 42 closed about it. 45 The rollers 51 are next moved inwardly to engage the outer face of the vertical leg of the angle, and to engage the gear teeth 4 and 52, by turning the screw 22, the vertical axis of the arms 28 then being coincident 50 with the center of the plate 3. Power is then applied to the winch controlling the cables 37. This causes each quadrant structure formed of the sleeve 29, rim 36 and bracket 41 to revolve about the vertical 55 pivot on the saddle 27, swinging the rollers 51 in an arc concentric to the curve of the forms and rolling the hot angle into close contact with the forms, the rollers rolling upon the angle by reason of the engagement of their teeth 52 with the gear teeth 4 on the plate 3. Since the long leg of the angle is held between the form and bed plate, it cannot buckle and a smooth even curve is imparted to the angle. When 60 the rollers reach the ends of the curved 65

forms, the ends 61 of the rims interlock, and the two quadrant structures together with the block 21 and bridge 23 move backwardly as one, the block 21 sliding in the bed plate ways 19, and the rollers 51 pressing the ends of the angle against the parallel faces 62 of the bed plate. When the operation is completed, the boxes 42 are disengaged and the quadrant structures are turned back to first position to free the rollers from the bent shape, the chain 56 hooked into the eye 53, the yoke 57 slipped over the arm sleeves, the key 7 removed, and the quadrants and geared plate lifted upwardly about their horizontal axes. The forms 9 may then be pushed inwardly to disengage from the bent shape, and the latter removed from the machine.

If shapes of greater curvature are to be bent, larger forms and larger gear plate 3 are substituted in the machine, the sleeves 29 being adjusted on the arms to properly position the rollers 51, and the faces 62 being built out with pieces of the required thickness.

In the above explanation we have considered a machine primarily adapted for bending angles with one of the legs on the inside of the curve. In Figures 8 and 9 are shown modifications to adapt the machine for bending angles with one of the legs on the outside of the curve. This is accomplished by providing a space between the bottom face 71 of the roller 51 and the upper face 72 of the bracket 41 in which the horizontal leg 17 of the angle is adapted to lie. The operation of the rollers and the related parts is otherwise the same. In this construction the shape of the guide boxes 42 is suitably altered, as shown in Figure 9, to accommodate the different position of the angle.

In Figure 10 is shown a machine adapted for bending channels. In this case a rider 73 is arranged on an extension 74 of each bracket 41, and is adapted to be carried around within the channel, between the roller and the form, so as to prevent the vertical walls 76 of the channel from being bent inwardly out of parallelism, during the bending process. In this construction also, the guide boxes 42 are altered in form to accommodate the different shape, but otherwise remain the same in function and operation as those first explained.

We claim:

1. In a machine for bending steel shapes, a bed plate, a form adapted to be seated on said bed plate, a second plate pivotally arranged on said bed plate for movement in a vertical plane for securing and supporting the form, a pair of arms meditately mounted on said bed plate for pivotal movement in both horizontal and vertical planes; a roller arranged on each arm in engagement with the shape on said form, means for moving each arm in a horizontal plane to cause the

rollers to press the shape against the form, and means for moving the arms and second plate in the vertical plane to permit the bent shape to be removed from the form.

- 5 2. In a machine for bending steel shapes, a bed plate, a form, means for releasably securing said form on said bed plate, a block slidably arranged on said bed plate, a saddle pivotally mounted in a horizontal 10 axis on said block, a pair of arms pivotally mounted in a vertical axis upon said saddle, a roller arranged on each arm in engagement with the shape on said form, and means for moving each arm about its pivot.
- 15 3. In a machine for bending steel shapes, a bed plate, a form, means for releasably securing said form on said bed plate, a pair of arms pivotally mounted on said bed plate, a roller arranged on each arm in engagement with the shape on said form, means 20 for moving each arm about its pivot, and means on each arm for supporting the shape in advance of the rollers comprising a box pivotally arranged on said arm, and shape 25 engaging rollers disposed therein.

4. In a machine for bending steel shapes, a bed plate, a form, a gear-toothed plate for

securing and supporting the form on said bed plate, a pair of arms pivotally mounted on said bed plate, a roller arranged on each arm and provided with gear teeth adapted to mesh with said gear-toothed plate, means for moving each arm about its pivot, and means for moving the arms to engage or disengage the rollers with the shape on said form and with the gear-toothed plate.

5. In a machine for bending steel shapes, a bed plate, a form disposed on said bed plate, a pair of arms meditately pivotally mounted on said bed plate, a roller arranged 40 on each arm in engagement with the shape on said form, a segmental grooved rim secured to each arm, and a cable engaging in said grooves and secured adjacent one end of the rims.

In testimony whereof we have hereunto set our hands at Oakland, California, this 31st day of July, 1919.

MEADER R. AKEY.
HERMAN KATZ.
